UNITED STATES PATENT OFFICE.

CHARLES F. TAYLOR, DECEASED, LATE OF HARTFORD, CONNECTICUT, BY STATE BANK AND TRUST COMPANY, A CORPORATION OF CONNECTICUT, EXECUTOR, OF HARTFORD, CONNECTICUT, AND GEORGE M. McCLELLAN, OF BURNSIDE, CONNECTICUT.

PAPER-CUTTING MACHINE.

1,180,088.

Specification of Letters Patent. Patented Apr. 18, 1916.

Application filed December 22, 1915. Serial No. 68,204.

To all whom it may concern:

Be it known that CHARLES F. TAYLOR, deceased, late a citizen of the United States residing at Hartford, in the county of Hartford and State of Connecticut, (of whose estate the STATE BANK AND TRUST COMPANY, a corporation of Connecticut, located in Hartford aforesaid, is executor, and of which corporation, executor, GEORGE H. BURT, a citizen of the United States, and resident of Hartford aforesaid, is vice-president,) and GEORGE M. McCLELLAN, of Burnside, in the county and State aforesaid, have invented certain new and useful Improvements in Paper-Cutting Machines, of which the following is a specification.

This invention relates to a machine for cutting paper, in piles or stacks, employing a broad and powerfully operated blade which in each descent thereof cuts through the pile properly positioned thereunder.

The object of this invention is to adapt the machine to automatically forwardly feed the stack or pile under the blade in successive uniform steps so that a pile of very large sheets placed on the table and automatically forwardly fed will be cut or subdivided into sections, all of which are uniform one with another and suitable for the making of tablets and stationery.

The invention comprises means for the forward step by step feed of the pile of paper on the table forwardly under the knife during the time the knife is stationary in its raised position. And as carried out the feed bar for advancing the paper works in conjunction with and is controlled by the mechanism which operates the knife, —the feed mechanism being actuated by the knife operating mechanism at the termination of the downward and upward return movement of the knife.

The invention, furthermore, comprises means whereby after the pile of paper has been advanced in its last step to be subjected to the last cut by the knife, the feed bar will be automatically retired rearwardly to its originally predetermined starting point for its action upon the next pile to be placed on the table of the machine.

The invention is described in conjunction with the accompanying drawings and is set forth in the claims.

In the drawings:—Figure 1 is a plan view

of a paper cutting machine having the mechanisms comprised in the invention applied thereon and forming part thereof. Fig. 2 is a side elevation of the machine. Fig. 3 is a rear elevation of the same. Fig. 4 is a partial sectional view on line 4—4, Fig. 3. Figs. 5 and 6 are elevations of portions of the mechanism included in the machine to be hereinafter described and identified. Fig. 7 is a sectional elevation of parts comprised in a clutch unshipping device to be hereinafter referred to, and Fig. 8 is a projected plan view of the shaft carried portion of Fig. 7.

In the drawings, A represents the table of the machine supported by the frame, of suitable design and operating vertically and at right angles to the table is the paper cutting knife B guided as usual in upright ways and operated under great power by the connection with the blade of the link a which is also connected with a short crank b carried on the shaft b^2 and operated through gearing c , c^2 , c^3 and c^4 , from the main shaft of the machine, driven by belt c^5 and pulley c^6 , such pulley being clutchable and unclutchable with and from the shaft.

In standard paper cutting machines of the kind to which this invention is adapted, the driving pulley is thrust into clutch through means of a handle lever C on a rockshaft C^2 for effecting the cycle of operation of the gearing and the downward and returning upward movement of the knife, and there is an automatic unclutching mechanism effected by the return rocking motion of the operating shaft C^2 which automatically acts on the completion of the ascent of the knife to throw the knife operating mechanism out of connection with the driving pulley or element.

D represents the feed bar having a width nearly or quite the same as that of the table and forwardly and rearwardly slidable thereon. The feed bar D is connected with and operated by a chain E^2 running around the sprocket wheels d and d^2 at the rear and front central portions of the machine, the rear sprocket wheel being mounted on a short stud shaft while the forward sprocket wheel d , d^2 is on a shaft e extending entirely across the front of the machine beneath the table.

The shaft *e* has a hand wheel *e*² thereon as usually provided for manually operating the feed bar. The shaft *e* also has on an end thereof, at one side of the machine another spring wheel *f* around which runs a sprocket chain *f*², such chain also running around another sprocket wheel *f*³ fixed on a sleeve *E* on a comparatively short transverse horizontal shaft *F* which is supported under the frame of the machine and projects outwardly beyond the side thereof. Also fixed on the said sleeve *E* is a comparatively large and fine toothed ratchet wheel *G* partially encircling the edge of which is an arc shaped guard *H* adjustable around the edge of the ratchet wheel through means of the slotted link *h*, one end of which is pivoted to the guard while the other slotted end portion is held in confinement by a screw stud *h*²—this device being effective when the slotted link is adjusted upwardly to position the guard to cover more of the upper edge of the ratchet than when the link is downwardly adjusted for withdrawing the guard to lessen the extent of the upper edge portion of the ratchet covered thereby. Suitably adjacent and parallel with the ratchet carrying sleeve *E* is a shaft *J* having a cam *K* thereon.

Loosely hung on the aforementioned sleeve supporting shaft *F* is an angular lever, one arm *i* carrying a pawl *i*² while the other arm *j* of such angular lever is provided with a roller *j*² with which said cam *K* coacts; and so that under each complete rotation of the shaft *J* the pawl will have an advancement around the edge of the ratchet wheel and then a retracting movement. In a greater or less portion of the forward thrust of the pawl, such pawl will be in engagement with the ratchet wheel as covered by the adjustable guard *H*. The annular pawl carried lever has the movement for the thrust of the pawl forcibly imparted thereto by the prominent portion of the cam and recedes to the depressed portion of the cam by gravity.

The cam carrying shaft *J* is free relatively to the pulley *L* which is constantly driven by the belt *L*²; but the said shaft has thereon a slidable clutch member *N* which may engage with and be disengaged from a companion clutch member *M* on the pulley *L*.

Parallel with the cam shaft *J* is a comparatively short slidable shaft *O* having a rigid arm or yoke *O*² in engagement with the grooved clutch member *N*; and this shaft has its inner end portion in proximity and at right angles to the rear end of the aforementioned rockshaft *C*² and which, it is to be remembered, is a part of the commonly and well known mechanism provided in the standard paper cutting machines for controlling the machine as to the starting and

stopping of the operation of the knife,—as paper cutting machines of the well known kind to which this invention relates include this controlling rockshaft and the shaft is well known as having a rocking motion in one direction when the handle lever is moved one way and a reverse rocking motion at the end of the knife elevating action, it is sufficient in the present connection to state that the rocking movements of this shaft are taken advantage of for controlling the action of the cam shaft *J*. The rear end of the said rockshaft *C*² has a short lever arm *C*³ provided with a hinged toe *C*⁴, such toe having a bevel *n* at one side of its extremity, a shoulder *m* or means for limiting its swinging movement in one direction, and a spring *o* for maintaining the toe in its normal position but against which the toe may be crowded when swung on its pivot *p*. The said toe carried on the lever arm *C*³ radially projected from the rockshaft intersects the bevel ended lug *q* affixed on the clutch operating shaft *o*.

When the paper cutting machine controlling rockshaft *C*² is swung to set the machine in operation for the descent and succeeding raising of the knife, the lever arm *C*³ with its pivot toe *C*⁴ is swung from a position understood as relatively to the left of the bevel ended lug on the clutch sliding shaft *O*, as Fig. 6 is viewed, to the position positively shown in such figure; and then when said rockshaft *C*² is automatically operated at the end of the ascent of the knife to be swung to the leftward, it, by its engagement with the non-beveled side of the lug *q* endwise forces the shaft and causes the sliding of the clutch member *N* into engagement with the clutch member *M* on the constantly driven pulley *L*. Now the cam shaft will have a rotation imparted thereto for the feeding impulse by the pawl to the ratchet wheel and causing, through the described connections between such ratchet wheel and the feed bar the forward feeding movement of such bar, and the advancement of the paper for one required step forwardly beyond and under the cutting plane of the knife. So soon as the cam shaft has made one complete revolution, it is automatically thrown out of clutch so that there may be but one feed step imparted to the paper in each period between every two cutting operations of the knife.

The means whereby the last described unclutching of the cam shaft is accomplished consists of a wedged shaped lug *t* on the clutch member *N* which coacts with the extremity of a bracket or small fixture *s* on the side of the frame, and which extremity projects into the revoluble path of the said lug *t*.

The member *N* immediately becoming clutched with the pulley partakes of the

rotary motion required for the cam shaft and at the completion of each rotation the wedge shaped lug t is brought to impingement against the extremity of the fixture s and by the latter crowded in a manner to slide the clutch member N out from its engagement with the clutch member of the pulley.

After a certain number of operations of the machine for a given number of cutting actions by the knife and feeding movements of the pile, so that the pile has been fed for its last step, the feed bar is automatically retired to a predetermined rearward position in readiness to have placed thereon a fresh pile to be additionally cut. The machine is rendered capable of such function by the provision of means as follows: On the shaft e which has the connection therewith of the chain drive for a feed bar, is a loose pulley u constantly driven through the cross belt u^2 from a pulley u^3 on the main or driving shaft c^4 of the machine. The shaft e has a peripherally grooved clutch member v slidable but non-rotatable thereon. Engaged with this clutch member is a shipper lever v^2 mounted to swing on pivot v^3 and having the comparatively short angularly extended arm v^4 projected within the machine frame and having connected therewith a comparatively long horizontally ranging bar v^5 provided with depending abutments v^6 and v^7 , which project across the path of movement of the feed bar D . After the paper has been forwardly fed to the extent of the making of its last cut, such bar will then in the next step be brought to strike the abutment v^6 , swinging the shipper lever v^2 to place the shaft e in clutch with the pulley u , whereupon through the rotation of shaft e in the proper direction the feed bar will be retired rearwardly on the table to the point as predetermined by the adjustment of the abutment carrying bar v^5 . When the rearward abutment v^7 is engaged by the rearwardly moving feed bar the clutch shifter lever is caused to be reversely swung to throw the shaft e out of driving connection with the pulley u , whereupon the feed bar will remain in its desired rearward position in readiness for the feeding of the fresh pile.

We claim:—

1. In a paper cutting machine, comprising a table, the reciprocatory knife, and an element for controlling the intermittent operations of the knife,—a feed bar resting on and movable relatively to the table and adapted to engage the rear edge of a pile of paper resting on the table, and means for imparting a succession of advancing step by step movements to the feed bar in a direction toward the knife, in the periods between those of the operations of the knife, which is automatically actuated by the said

element which controls the operation of the knife.

2. In a paper cutting machine, comprising a table, the reciprocatory knife, and an element for controlling the intermittent operations of the knife,—a feed bar resting on and movable relatively to the table and adapted to engage the rear edge of a pile of paper resting on the table, means for imparting a succession of advancing step by step movements to the feed bar in a direction toward the knife, which is automatically actuated by the said element which controls the operation of the knife, and automatic means for rearwardly retiring the feed bar, after the same shall have been intermittently advanced to within a given proximity to the knife, operatively controlled by the feed bar.

3. In a paper cutting machine, the table, a reciprocatory knife, and an element for controlling the intermittent operations of the knife,—a feed bar movable on the table, a ratchet wheel, a swinging pawl carrier having a pawl coacting with said ratchet wheel, a rotative shaft having a cam coacting with said pawl carrier, connections between said ratchet wheel and said feed bar whereby on the pawl-imparted impulses of the ratchet wheel the feed bar will have a correspondingly advancing movement, and means for imparting, intermittently, single rotations to the cam-provided shaft.

4. In a paper cutting machine, the table, a reciprocatory knife, and an element for controlling the intermittent operations of the knife,—a feed bar movable on the table, a ratchet wheel, a swinging pawl carrier having a pawl coacting with said ratchet wheel, a rotative shaft having a cam coacting with said pawl carrier, connections between said ratchet wheel and said feed bar whereby on the pawl-imparted impulses of the ratchet wheel the feed bar will have a correspondingly advancing movement, a guard for controlling the extent of the working thrusts by the pawl to the ratchet wheel, and means for intermittently rotating the cam shaft.

5. In a paper cutting machine, the table, a reciprocatory knife, and an element for controlling the intermittent operation of the knife,—a feed bar movable on the table, a ratchet wheel, a swinging pawl carrier having a pawl coacting with said ratchet wheel, a rotative shaft having a cam coacting with said pawl carrier, connections between said ratchet wheel and said feed bar whereby on the pawl-imparted impulses of the ratchet wheel the feed bar will have a correspondingly advancing movement, a driving wheel appurtenant to said cam provided shaft, a member slidable on the cam shaft, clutchable with and unclutchable from, said driving wheel, means operable by the said element which controls the intermittent opera-

tions of the knife to place the cam shaft in clutch with the said driving wheel therefor, and means for moving the clutch member out of clutch after a rotation of the cam shaft.

6. In a paper cutting machine, the table, a reciprocatory knife, and an element for controlling the intermittent operations of the knife,—a feed bar movable on the table, 10 a ratchet wheel, a swinging pawl carrier having a pawl coacting with said ratchet wheel, an arc shaped guard covering a portion of the edge of the ratchet wheel in the path of the pawl, a rotative shaft having a cam coacting with the pawl carrier, connections between said ratchet wheel and said feed bar whereby on the pawl-imparted impulses of the ratchet wheel the feed bar will have a correspondingly advancing movement, 15 a driving wheel appurtenant to said cam provided shaft, a member non-rotative relatively to, but slideable on, the cam shaft, clutchable with and unclutchable from, said driving wheel, means operable by the said element which controls the intermittent operations of the knife to place the cam shaft in clutch with the said driving wheel therefor, and means for throwing the said clutch member out of clutch after a rotation of the 20 cam shaft.

7. In a paper cutting machine, the table, a ratchet wheel, a swinging pawl carrier having a pawl coacting with said ratchet wheel, an arc shaped guard covering a portion of the edge of the ratchet wheel in the path of the pawl, means for adjusting the 25 guard as to its position relatively to the circumference of the ratchet wheel, a rotative shaft having a cam coacting with the pawl carrier, connections between said ratchet wheel and said feed bar whereby on the pawl-imparted impulses of the ratchet wheel the feed bar will have a correspondingly advancing movement, 30 a driving wheel appurtenant to said cam provided shaft, a member non-rotative relatively to, but slideable on, the cam shaft, clutchable with and unclutchable from, said driving wheel, means operable by the said element which controls the intermittent operations of the knife to place the cam shaft in clutch with the said 35 driving wheel therefor, and means for throwing the said clutch member out of clutch after a rotation of the cam shaft.

8. In a paper cutting machine, the table, a reciprocatory knife, and a rock shaft for controlling the intermittent operation of the 40 knife,—having a lever provided with a jointed toe, yieldable in one direction only,—a feed bar movable on the table, a ratchet wheel, a swinging pawl carrier having a pawl coacting with said ratchet wheel, a 45

rotative shaft having a cam coacting with said pawl carrier, connections between said ratchet wheel and said feed bar whereby on the pawl-imparted impulses of the ratchet wheel the feed bar will have a correspondingly advancing movement, a driving wheel appurtenant to said cam provided shaft, and loose relatively thereto, a member slideable on the cam shaft, clutchable with, and unclutchable from, said driving wheel, a slide 50 rod having a bevel sided projection in the range of swinging movement of the toe provided lever of said rockshaft, and having a yoke engaging the slideable clutch member, operable when the rock shaft is rocked 55 in one direction, and the rod is slid, to move the clutch member into clutch, and means for automatically moving the said clutch member out of clutch after a rotation of the cam shaft.

9. In a paper cutting machine, a table, a reciprocatory knife and an element for controlling the intermittent operation of the knife, a feed bar movable on the table, a ratchet wheel, a swinging pawl carrier 60 having a pawl coacting with the ratchet wheel, a rotative shaft having a cam coacting with said pawl carrier, connections between said ratchet wheel and said feed bar whereby on the pawl-imparted impulses of the ratchet wheel the feed bar will have its advancing movement, a driving wheel appurtenant to said cam shaft and loose relatively thereto, a member slideable on the cam shaft, clutchable with, and unclutchable 65 from, said driving wheel and provided with a portion having an inclined face, means operable by the said controlling element to move the said slideable member in clutch with said driving wheel therefor and a fixture adjacent the slideable clutch member and to intersect the path of revoluble movement of said inclined face portion thereon for automatically moving the clutch member out of clutch after a rotation of the cam 70 shaft.

10. In a paper cutting machine, the table, a reciprocatory knife, and a rock shaft for controlling the intermittent operation of the knife,—having a lever provided with a jointed toe, yieldable in one direction only,—a feed bar movable on the table, a ratchet wheel, a swinging pawl carrier having a pawl coacting with said ratchet wheel, a rotative shaft having a cam coacting with 75 said pawl carrier, connections between said ratchet wheel and said feed bar whereby on the pawl-imparted impulses of the ratchet wheel the feed bar will have a correspondingly advancing movement, a driving wheel appurtenant to said cam provided shaft, and loose relatively thereto, a member slideable on the cam shaft, clutchable with, and unclutchable from, said driving wheel, and having an inclined face portion, a slide rod 80

having a bevel sided projection in the range of swinging movement of the toe provided lever of said rockshaft, and having a yoke engaging the slideable clutch member, operable when the rock shaft is rocked in one direction, and the rod is slid, to move the clutch member into clutch, and a fixed adjacent slideable clutch member to intersect the path of revolute movement of said inclined face portion thereon for automatically moving the clutch member out of clutch after a rotation of the cam shaft.

11. In a paper cutting machine, the feed bar and a shaft having connections between same and the bar whereby on rotative movements of the shaft the bar will be advanced, a driving wheel appurtenant and loose relatively to said shaft, and a clutch member on the shaft movable to place the shaft in and out of clutch with the driving wheel, a shifter lever for said clutch provided with a bar ranging in the line of movement

of the feed bar and having abutments at opposite end portions thereof extended across the path of the feed bar and operable on the advancement of the feed bar to its predetermined limit to place said shaft in clutch with the driving wheel therefor to cause the rearward retirement of the feed bar and also operable at the end of the rearward movement of such bar to reverse the clutch operating lever whereby said clutch member is disengaged from said driving wheel.
